UNITED STATES PATENT OFFICE.

CHARLES H. FOSTER, OF NEW YORK, N. Y., ASSIGNOR TO THE UNION SPECIAL SEWING MACHINE COMPANY, OF CHICAGO, ILLINOIS, A CORPORATION OF ILLINOIS.

THREAD-CUTTING DEVICE FOR SEWING-MACHINES.

No. 876,512.

Specification of Letters Patent.

Patented Dec. 31, 1907.

Application filed April 5, 1899. Serial No. 711,801.

To all whom it may concern:

Be it known that I, CHARLES H. FOSTER, a citizen of the United States, residing at New York city, in the county of New York, State of New York, have invented certain new and useful Improvements in Thread-Cutting Devices for Sewing-Machines, of which the following is a description, reference being had to the accompanying drawing, and to the letters and figures of reference marked thereon.

My invention relates to an improvement in sewing machines, and the especial object of the invention is to provide a cutting attachment for severing the stitches after a piece of goods has been passed through the machine.

The improvement originated with special reference to apparatus for the sewing of filled bags, where a sewing machine of the Union Special cylindrical bed type is arranged in approximately vertical position and the filled bags fed along on an endless carrier to the sewing mechanism. It is desirable after the sewing of the mouth of the bag has been accomplished to continue the sewing operation until the next bag is reached, thereby leaving a chain of stitching between any two bags, and my improvement consists in a cutting arrangement adapted to be attached to the machine for severing this chain between two bags in the quickest possible manner, in order to save the time of the operator.

While I have referred to this improvement in this connection, it will be understood that I do not wish to be limited to the type of sewing machines to which the attachment is applied, nor to the especial work designed to be performed by the attachment, for it is applicable to flat as well as cylindrical bed machines and for severing of the stitches after any piece of work has been sewed.

The invention consists in the matters hereinafter described and referred to in the appended claims.

The invention is illustrated in the accompanying drawings, in which

Figure 1 is a side elevation of the end of a bag sewing machine shown in working position, to which my invention has been applied; Fig. 2 is a perspective end view of a Union Special cylinder machine embodying the invention; Fig. 3 is an end elevation of Fig. 2. Fig. 4 is a rear end view showing a different form of cutting apparatus from that of Figs. 1, 2, and 3; and Fig. 5 is a detail

view of the cutting apparatus and connecting parts shown in Fig. 4.

In these drawings, A represents the bed of the machine herein shown as cylindrical but as above stated, any form of bed may be used. B is the goose neck of the machine, C the needle bar, D the presser bar, E the presser foot, and F the presser bar spring, all these parts being of a well known type.

Referring to Figs. 1, 2, and 3, the bar G which is ordinarily used as a supplemental presser bar to prevent the swinging of the presser foot, being connected thereto by the cross bar H, is provided on its lower end with a plate or head I to which is screwed a cutting blade J, which is adapted to cut against a block or anvil K, screwed to the bed of the machine. The bar G is narrowed and squared off as shown at L and the inner end of the cross bar H is slotted to form guides M between which the bar G is properly moved and prevented from swinging. This bar G is normally held in raised position by means of a spring N attached to the head I at one end and at the other end in any suitable manner to the head of the machine. As ordinarily constructed, this supplemental presser bar and main presser bar D are connected by the cross bar H, which is rigidly attached to both said bars, and, therefore, as the presser bar is raised by the ordinary cam lever or treadle, so also the supplemental presser bar is raised, the rigid connection between the two preventing the presser bar from swinging to bring the needle hole out of alignment with the needle. In the present construction, by means of the slotting of the cross bar H to form the guides M, it will be noticed that this connection is made an accommodating one, thus allowing the supplemental bar which carries the cutter to move up and down irrespective of the presser bar and the presser bar can be elevated by the ordinary lifter without disturbing the position of the guide bar, while at the same time, no swinging of the presser bar is permitted, this being one of the features of my invention.

The bar G is operated to give the cutting action by means of an angle lever O fulcrumed at P to the goose neck of the machine, the short arm Q normally resting on top of the bar G and the long arm R having attached to its lower end a chain S, which runs over a pulley and by suitable connections

to a treadle, convenient to the foot of the operator, so that by pressing on the treadle the angle arm is swung on its pivot and the short arm Q forces down the bar G and causes 5 the knife to perform its cutting action.

In Figs. 4 and 5 another form of cutting arrangement is shown, in which instead of the head I and cutting blade J, there is pivoted to the lower end of the bar G, one 10 blade S of a pair of shears, while the other blade T is rigidly secured or formed with the bar G.

The blade S has a projecting part U to which is pivoted the lower end of a lever V, 15 pivoted at its upper end to the head of the machine, as shown at W, and it will be seen that as the arm Q presses down on the upper end of the bar G, the pivoted blade S will close against the stationary blade and 20 form the work of cutting off the chain.

It will be noticed that in a bag sewing machine as arranged in Fig. 1, the driving shaft will be in an approximately vertical position, while the supplemental bar G carrying the 25 cutter reciprocates at right angles thereto and against the anvil or block K, secured to the work plate of the machine this also being one of the features of my invention.

Various minor modifications and changes 30 may be made without departing from the spirit of my invention.

Having thus described my invention, what I claim as new, and desire to secure by Letters Patent, is:

35 1. In an apparatus for severing the threads between filled sacks, the combination with a sewing machine having an approximately vertical bed plate and an overhanging arm, a horizontally arranged presser 40 bar mounted on said arm, carrying a presser foot, coöperating feed mechanism, and a horizontal cutter bar parallel with the presser bar and also mounted on said arm, but having longitudinal movement independent 45 thereof, and a coöperating stationary member, the cutting edges being arranged transverse to the line of feed, means for preventing the cutter bar from turning and means for moving the cutter bar longitudinally; 50 substantially as described.

2. In a sewing machine, having an approximately vertical bed plate, a horizontally arranged presser bar carrying a presser foot with coöperating feed mechanism, mechanism for severing the chain of stitching after 55 the sewing has been effected, including a horizontal cutter bar having longitudinal movement independent of the presser bar and a coöperating member, with their cutting edges transverse to the line of feed, with 60

means for operating the cutter bar, said means including a swinging lever pivoted to the machine frame, one arm of which in its movement engages the horizontal cutter bar, and the other arm extending within 65 reach of the operator, and a spring for keeping the cutter bar normally retracted; substantially as described.

3. A sewing machine having an approximately vertical bed plate, a horizontally arranged presser bar carrying a presser foot, with coöperating feed mechanism, a bar parallel with the presser bar and connected with the latter to prevent swinging thereof but having longitudinal movement independent 75 of said presser bar, a cutting member carried by said bar, with its cutting edge operating across the line of feed, a coöperating stationary cutting member rigidly attached to a part of the machine frame, and 80 means for operating the movable cutting member; substantially as described.

4. In a sewing machine having an approximately vertical cylindrical bed plate and stitch-forming mechanism, mechanism 85 for severing the chain of stitching after the sewing has been effected, comprising a horizontally moving cutter bar with its cutting edge transverse to the line of feed of the machine, and a coöperating striking block 90 or anvil secured to the outside of said cylindrical casing or bed plate, and in line with said cutting edge, means for preventing said cutting bar from turning and means for operating said cutting bar, substantially as 95 described.

5. In a sewing machine having an approximately vertical bed plate, a horizontally arranged presser bar, a presser foot carried thereby, a cutter bar having a cross bar connection with the presser bar to permit swinging movement of the latter, but having an independent longitudinal movement, a cutting blade carried by the cutter bar, a spring attached at one end to a stationary part of 100 the machine frame, and at the other end attached to the cutter bar, and a swinging lever pivoted to the machine frame, one arm of which in its movement engages the cutter bar, and the other arm extending within 105 reach of the operator, and a striking block arranged on the bed plate of the machine in line with the cutting blade; substantially as described.

In testimony whereof I affix my signature, 115 in presence of two witnesses.

CHARLES H. FOSTER.
